MOTION PICTURE CAMERA

Albert S. Howell, Chicago, Ill., assignor to The
Bell & Howell Company, Chicago, Ill., a corpora-
tion of Illinois

Application September 26, 1932, Serial No. 634,934

10 Claims. (Cl. 88—16)

My invention relates particularly to motion picture cameras of the type in which a film strip is run through the camera a plurality of times to expose different longitudinal sections of the film strip, and the general object of the invention resides in the provision of a novel motion picture camera of the above type which is simple and convenient.

With this object in view my invention consists 10 in certain features of novelty by which this and certain other objects, hereinafter appearing, are effected, all as fully described with reference to the accompanying drawings and more particularly pointed out in the appended claims.

15 In the said drawings—

Figure 1 is a side elevation of a motion picture camera embodying my invention;

Figure 2 is a front elevation of the same;

Figure 3 is a similar elevation showing the camera in its relatively upside down position, 20 hereinafter described;

Figure 4 is a plan view of the same;

Figure 5 is an enlarged side elevation of the same with the cover of the camera casing removed and with parts broken away and shown in section;

Figure 6 is a plan view with parts broken away and shown in section;

Figure 7 is a partial front elevation of a portion 30 of the mechanism hereinafter described;

Figure 8 is a sectional view substantially on the line 8—8 of Figure 6;

Figure 9 is a sectional view substantially on the line 9—9 of Figure 8;

Figure 10 is a sectional view substantially on the line 10—10 of Figure 6;

Figure 11 is a sectional view substantially on the line 11—11 of Figure 5;

Figure 12 is a partial sectional view substantially on the line 12—12 of Figure 8;

Figure 13 is a partial sectional view on the line 13—13 of Figure 2;

Figures 14, 15, 16 and 17 are similar diagrammatic views of a portion of the mechanism showing different positions thereof;

Figure 18 is a plan sectional view of the film cartridge of my invention;

Figure 19 is a bottom plan view of the same;

Figure 20 is an axial section of the magazine 50 with the film removed and taken on the line 20—20 of Figure 19;

Figure 21 is a face view of a motion picture film used in the camera;

Figure 22 is a face view of the same after exposure and development; and

Figure 23 is a face view of the developed film after splitting and splicing for projection as hereinafter described.

Like characters of reference indicate like parts in the several views.

Referring to the drawings, 1 designates a camera casing which is inclusive of a cover 2 closing a side opening thereof and detachably secured on the casing by a releasable locking device generally designated at 3. See Figures 1 to 4 10 and 9. Arranged intermediately within the casing are parallel frame plates 4 and 5 disposed in vertical forwardly and rearwardly extending planes.

The innermost frame plate 5 adjoins a spring 15 motor housing 6 on the side of the camera opposite the open side thereof, and arranged within the housing 6 and disposed on a transverse axis is a spring motor, see Figure 9, consisting of a revolute hub 7 provided with an axial bore having a clutch formation 8 for engagement with a winding key 9 shown in Figure 2, a stationary bored member 11 disposed coaxially with the hub 7, a spring brake coil 12 operative between the hub 7 and member 11 to permit rotation of the hub in only one direction; a spiral power spring 13 having its inner end secured with the hub 7 and disposed within and having its outer end secured with a revolute cup shaped spring casing member 14 which is rotated by the power spring. 20

A revolute shaft 15 extends transversely within the motor housing 6 and between the frame plates 4 and 5, and has a pinion 16 secured thereon within the motor housing and meshing with gear teeth 17 formed on the periphery of the spring casing member 14 for the driving of the shaft 15 from the spring motor. See Figures 8, 10 25 and 12.

Secured on the shaft 15 and disposed between the frame plates 4 and 5 is a large spiral gear 18 which meshes with a small spiral pinion 19 secured on one end portion of a vertically arranged revolute shaft 21, disposed rearwardly between the frame plates, for the driving of this shaft. See Figure 8.

Secured on the shaft 21 adjacent its other end is a pair of spaced spur gears 22 and meshing with one of these gears is a revolute spur gear 23. See Figures 6 and 8. A revolute spur gear 24 meshes with the other of the gears 22 and another revolute spur gear 25 meshes with the gear 24, the gears 23 and 25 being spaced and driven in opposite directions from the shaft 21.

Another revolute vertically arranged shaft 26 is disposed forwardly between the frame plates 55

4 and 5 and angularly secured with this shaft and slidable thereon is a shiftable member 27 which is provided with a spur gear 28 which may mesh with either of the gears 23 and 25, by shifting of the member 27, to drive the shaft 26 in either direction from the shaft 21, the gear 28 having an intermediate position between the gears 23 and 25 in which it is not meshed with either of the gears 23 and 25.

10 A forwardly and rearwardly extending revolvable shaft 29 is provided at its forward portion with a spiral gear 30 which meshes with a spiral gear 31 secured on the intermediate portion of the shaft 21, and the shaft 29 is connected with 15 a suitable speed governor, generally indicated at 32 and enclosed in a rearwardly projecting chamber 33 of the casing 1, for effecting a controlled uniform speed of the shaft 21 and the mechanism driven thereby. See Figure 8.

20 The portion of the interior of the casing 1 between the plate 4 and the cover 2 comprises the film chamber, and disposed forwardly in this chamber and intermediately of the camera vertically is a transversely disposed intermittent film 25 feed exposure guide which consists as follows, see Figures 5, 9 and 11.

A rear guide plate 34 is secured against the outer face of the frame plate 4 by means of headed shoulder screws 35 passing through apertures in this frame plate and screwthreaded into the guide plate, and a front guide plate 36 has a rearwardly extending portion 37 mounted for forward and rearward sliding movement on the inner face of the frame plate 4 by means of forwardly and rearwardly extending slotted portions of the portion 37 engaging the screws 35 under the heads thereof and a rearwardly disposed stud 38 on the frame plate 4, a spring 39 secured at its opposite ends with the stud 38 and the portions 37 yieldably urging and normally maintaining the front guide plate in its rearward or closed guide position.

When in adjacent relation as shown, the guide plates 34 and 36 form a vertical channel 41, see 45 Figure 9, for the feeding of a film strip therethrough, the guide plate 36 being moved forwardly for the lacing of the film strip therein.

A revolvable transverse shaft 42 extends between the frame plates 4 and 5 and is provided with a 50 spiral gear 43 therebetween which meshes with a spiral gear 44 secured on the shaft 26 for the driving of the shaft 42, and secured on the shaft 42 immediately outward of the frame plate 4 are two heart shaped cams 45 and 46. See Figures 55 5, 8, 9 and 12.

Two superposed shuttles 47 and 48 are disposed immediately outward of the frame plate 4 and are pivotally and slidably mounted at their rear ends, by means of slots 49 therethrough, on a 60 headed shoulder screw 51 mounted on the frame plate 4.

The intermediate portions of the shuttles are enlarged and are provided with rectangular openings 52 and 53, of which the cam opening 52 of 65 the shuttle 47 is engaged by the inner cam 45 and the cam opening 53 of the shuttle 48 is engaged by the cam 46.

The front portions of the shuttles 47 and 48 are provided with film strip perforation engaging 70 teeth 54 and 55, the tooth 54 of the shuttle 47 being slidably engaged for forward and rearward engaging movement in an aperture 56 through the rear film guide plate 34 while the tooth 55 of the shuttle 48 is slidably engaged for rectangular movement in a vertical forwardly and 75

rearwardly extending plane in a vertical slot 57 through the rear film guide plate. See Figures 5 and 11.

The cam opening 52 of the shuttle 47 is engaged by the cam 45 only at the vertical sides thereof so that this shuttle receives only a forward and rearward reciprocating movement as the shaft 42 is rotated. The cam opening 53 of the shuttle 48 is engaged by the cam 46 on the four sides thereof so that the tooth 55 of the shuttle receives a rectangular movement as the shaft 42 is rotated.

The cams 45 and 46 are set at 180° so that in feeding a film in the guide the shuttle 48 intermittently engages perforations of a film strip in the guide to intermittently feed the same while the shuttle 47 intermittently engages perforations of the film strip in alternation with the shuttle 48 to register the film strip during the periods of rest thereof, it being observed that this intermittent feed mechanism is operable in either direction to feed a film strip in either direction.

A revolvable forwardly and rearwardly extending shaft 58 is disposed between the frame plates 4 and 5 adjacent the intermittent film feed guide and is provided with a spiral gear 59 on its rear end which meshes with another spiral gear 61 secured on the shaft 26 for the driving of the shaft 58 therefrom. Secured on the forward portion of the shaft 58 is a segmental light shutter 62 which sweeps in front of the intermittent feed guide for intermittently cutting off the exposure light therefrom during feeding movement of the film strip in the guide.

The front guide plate 36 is provided with transversely aligned exposure apertures 63, each adapted to expose substantially one-half of the picture area of the film strip in the guide transversely of the film strip, and arranged immediately in front of the guide plate and vertically shiftable, in a manner hereinafter described is a shutter plate 64 provided with transversely arranged vertically staggered exposure apertures 65 vertically aligned respectively with the apertures 63, so that either of two longitudinal sections of a film strip fed through the intermittent feed guide may be progressively exposed. See Figures 5, 9 and 11.

Mounted for rotation in a bore in the front wall of the casing in front of the intermittent feed guide is a lens mount member 66 in an eccentric bore of which a photographic lens 67 is mounted for angular shifting movement to align with either of the exposure apertures 63 of the front guide plate 36, the lens being shifted to align with the aperture 63 which is uncovered by the respective aperture 65 of the shutter plate 64 to photographically expose the respective longitudinal section of the film strip fed through the guide.

The reversible intermittent film feeding mechanism of the camera together with the exposure shutter 62 are driven from the shaft 26, hereinbefore described, so that the direction of operation of the feeding mechanism and the exposure shutter may be reversed by shifting the gear 28 from engagement with one of the gears 23 and 25 into engagement with the other, as hereinbefore described.

The purpose of this arrangement is to provide for progressively exposing one longitudinal section of a film strip with the normal action of this section running in one direction and to subsequently progressively expose the other longitudinal section of the film strip with the normal

action of the latter section running in the opposite direction.

To illustrate reference is directed to Figures 21, 22 and 23. Figure 21 illustrates at 68 a motion picture film strip which is preferably double perforated, that is to say, it is provided with longitudinally spaced feed perforations 69 at both margins thereof.

After exposure and development, see Figure 22, 10 the film 68 has two longitudinal sections of pictures 71 with their normal action running in opposite directions as indicated by the arrows in this figure, which may be projected by first running the film strip in one direction and then 15 running it in the opposite direction, or preferably, where the film strip is double perforated as shown, splitting the film strip along its center and splicing the separated half width strips together with the picture sections and perforations 20 of the two half width strips aligned and with the normal action of the two picture sections running in the same direction for projection from the half width double length film strip without reversing the feed of the strip.

25 The splice is indicated at 72 in Figure 23 and the arrows indicate the direction of normal action of the succeeding picture sections.

The method of my invention of operating the camera resides in exposing one of the longitudinal sections of the film strip while the strip is fed in one direction and subsequently exposing the other longitudinal section of the film strip while the strip is fed in the other direction and with the camera in a relatively upside down position, the initial operating position of the camera for exposing the first longitudinal section of the film strip being shown in Figures 1 and 2, and the opposite or relatively upside down position of the camera for exposing the other longitudinal section of the film strip being shown in Figure 3.

In carrying out the method of my invention the lens 67 and the shutter plate 64 are positioned correspondingly to expose one longitudinal section of the film while the gear 28 is 45 engaged with one of the gears 23 and 25 to feed the film strip in one direction. Then the lens 67 and shutter plate 64 are shifted correspondingly to expose the other longitudinal section and the gear 28 is shifted to feed the film strip in the opposite direction and said other longitudinal section of the film strip is exposed with the camera in the aforesaid relatively upside down position.

In order to facilitate the positioning of the various devices for exposing the two longitudinal sections of the film strip, as above described, and to render the operation of the camera in the aforesaid opposite operating positions thereof convenient, the following is provided.

A plate 73 is slidably mounted on the outer 60 face of the frame plate 5 for vertical shifting movement parallel to the shafts 21 and 26 by means of headed shoulder screws 74 passing through slots 75 in the plate 73 and screw-threaded into the plate 5. See Figures 8, 9, 11 and 12.

65 A forwardly and rearwardly disposed U-shaped spring member 76 has its closed end disposed rearwardly and has one leg thereof secured, by means of screws 77, on the plate 73 and has the free end of the other leg thereof engaged in a shifting groove formation 78 on the shiftable member 21 whereby the gear 28 is shiftable with the plate 73 to engage either of the gears 23 and 28 to drive the film feeding mechanism in either 75 direction.

The shutter plate 64 extends inwardly from the front guide plate 36 and has its inner end angled and secured to the plate 73, as designated at 79, whereby the shutter plate is shiftable with the plate 73 and gear 28 to expose one longitudinal section of the film strip when the gear 28 is engaged with one of the gears 23 and 25 to feed the film strip in one direction and to expose the other longitudinal section of the film strip when the gear 28 is engaged with the other of the gears 23 and 25 to feed the film in the opposite direction.

The forward portion of the plate 73 is angled to lie parallel with the front of the camera, as designated at 81, and this portion of the plate is provided with a vertical gear rack 82 which 15 meshes with the smaller of two coaxial gears 83 and 84 fixed with each other and mounted for rotation on the axis of the shutter shaft 58. See Figures 8, 9 and 11.

The larger gear 84 meshes with a gear 85 on 20 the lens mount member 66, whereby shifting of the plate 73 from either end of its movement to the other effects movement of the lens mount member 66 and the lens 67, mounted eccentrically thereon, through an angle of 180° to align 25 the lens with the exposure aperture 63 which is uncovered by the shutter plate 64 for the photographic exposure of the corresponding longitudinal section of the film strip.

Operation of the camera is manually controlled 30 to start and stop the same in the following manner.

A forwardly disposed vertical rod 86 is slidably mounted on the plate 73 by means of spaced bearings 87, rotation of the rod being prevented by a 35 radially projecting pin 88 slidably engaging in a vertical slot 89 in the plate 73. See Figures 8 and 11. Arranged on the rod are spaced stop members 91 which are disposed to lie in the path of the exposure shutter 62 to be engaged by the 40 radial edges thereof and thus stop operation of the camera when the rod 86 is disposed at the corresponding ends of its movement, the stop members 91 being arranged to lie out of the path 45 of the shutter 62 when the rod is in an intermediate position of its movement to permit operation of the camera.

A spring arm 92 is formed integrally with the shift member 76 and accordingly has its rear end secured with the plate 73, and the forward or free 50 end of this arm is engaged in a slotted shifting formation 93 on the rod 86, whereby the rod 86 is shifted with the plate 73 to its opposite positions in which one or the other of the stop members 91 is engaged by the shutter 62 to stop operation 55 of the camera.

By reason of the arm 92 being resilient, the rod 86 may be moved from either end of its movement to its intermediate position for release of the shutter 62 for operation of the camera, the 60 arm 92 returning the rod to the end of its movement corresponding with the position of the plate 73 when the rod is released to stop operation of the camera.

65 Slidably engaged in counterbored bores through the opposite horizontal end walls of the casing 1 and accessible from these sides of the camera, are push buttons 94, the shanks of which extend into the casing and are pivotally connected with corresponding ends of levers 95 within the casing 70 which are intermediately pivoted, as designated at 96. See Figure 11. Compression springs 97, encircling the shanks of the push buttons and reacting on the casing, engage against the heads of the push buttons 94 and yieldably urge the 75

- push buttons outwardly and normally maintain them in their outer positions, stops 98 being engaged by the levers 95 to limit outward movement of the push buttons.
- 5 The other ends of the levers 95 lie adjacent the rod 86, and radial pins 99 on the rod 86 are disposed so that one or the other is within the operative range of the corresponding lever 95, dependent upon the position of the shift plate 73, so that
- 10 only one of the push buttons is operative at one time to actuate the rod 86 to release the camera mechanism for operation thereof, this serving as an indication to the operator as to the proper position in which the camera is to be held for the
- 15 proper exposure of the film strip during the instant run of the film strip in the camera, the arrangement being such that the camera should be positioned with the operative push button at the top.
- 20 Two view finders 101 of the enclosed tube type are arranged on the upper and lower ends of the casing 1 and are thus disposed in opposite relation with the exposure region of the camera for alternate use, one in one photographic position of the camera during progressive exposure of the film strip in one direction and the other in the other photographing or relatively upside down position of the camera, the view finder which is at the top of the camera being the one
- 25 used.
- 30 In order to additionally indicate to the operator the proper position in which the camera is to be held for the proper exposure of the film strip during the instant run of the camera, the ends of the rod 86 are so arranged that as the shift plate 73 is positioned for one or the other run of the film strip, the adjacent end of the rod is projected through a suitable bore 102 into the tube of the view finder which should be at the bottom
- 40 during the instant run of the film strip, thus cutting off the view through this view finder to render it functionless. See Figures 11 and 12. This alternate rendering of the view finders functionless is an indication to the operator as to the
- 45 proper position of the camera in an obvious manner.
- Secured on the side of the spring casing 14 adjacent the frame plate 5, see Figures 9 and 10, is a modified Geneva movement cam 103 having a
- 50 projecting tooth 104 disposed between two flutes 105. A star wheel 106 is rotatably mounted on the frame plate 5 in cooperating relation with the cam 103 and is moved one tooth with each revolution of the cam and spring casing.
- 55 A latch plate 107 is disposed forwardly of the star wheel 106 between the frame plate 5 and the spring casing 14 and is mounted for forward and rearward movement by means of studs 108 on the frame plate and engaged in slots 109 in
- 60 the latch plate. The latch plate has secured thereto a rearwardly projecting spring arm 111 the rear end of which is enlarged for engagement with a full tooth 112 of the star wheel to move the latch plate forwardly from its rear position, the remainder of the teeth of the star wheel being cut away, as designated at 113, to clear the arm 111. A spring 114 yieldably urges the latch plate rearwardly and normally maintains it in its rearward or locking position.
- 65 The latch plate 107 is provided with a vertical slot 115 the forward edge of which is formed with terminal locking notches 116. A stud 117 is mounted on the shift plate 73 and engages in the slot 115, so that the terminal notches 116
- 70 engage the stud 117 under the influence of the
- 75 spring 114 to lock the shift plate at the opposite ends of its movement.
- The shift plate 73 is yieldably urged into an intermediate position from either end of its movement by opposing balanced springs 118, so that, 5 upon forward movement of the latch plate to release the stud 117 from the engaged notch 116 of the latch plate, the shift plate 73 is moved to its intermediate position.
- The drive shaft 21 is provided with a diametrically projecting pin 119, see Figure 8, and when the shift plate 73 is in its aforesaid intermediate position, the transverse portion of the U-shaped spring shift member 76 lies in the path of this pin and is engaged thereby to stop 10 operation of the mechanism, the shifting, as shown the partial shifting, of the reversible driving means and of the exposure means being effected as an incident of the stoppage of the mechanism.
- 15 As a run of the camera is made the star wheel 106 is periodically advanced until a predetermined run is made, whereupon the full tooth 112 engages the arm 111 and moves the latch plate 107 forwardly to release the shift plate 73 which upon release moves to its intermediate position, resulting in stoppage of the mechanism and shifting of the reversible driving means and the exposure means.
- 20 The shift plate 73 is manually shifted from its intermediate position to the proper end of its movement for the initial run of the film by a transversely projecting extension 121 to which the springs 118 are attached and which projects through a vertical slot 122 in the frame plate 4 for manual operation of the shift plate when the cover 2 is removed. See Figures 5 and 8.
- 25 The shift plate 73 is manually shifted from its intermediate position to the proper end of its movement for the initial run of the film by a transversely projecting extension 121 to which the springs 118 are attached and which projects through a vertical slot 122 in the frame plate 35 for manual operation of the shift plate when the cover 2 is removed. See Figures 5 and 8.
- 30 The camera having been loaded with film, as hereinafter described and the shift plate 73 set for the initial run of the film strip, the cover 2 is latched on the casing 1, after which the first section of the film strip is exposed. The initial predetermined run of the film strip having been completed, the mechanism is stopped and the shift plate is moved into its intermediate position automatically as hereinbefore described, the operator receiving indication by the inoperativeness of the camera.
- 35 The shift plate 73 is then manually positioned at the other end of its movement for the reverse run of the film strip without opening of the camera in a manner now to be described.
- 40 The transverse portion 81 of the shift plate 73 is extended at one end with a relatively wide portion 123 which underlies an aperture 124 through the front wall of the casing 1 in all positions of the shift plate. See Figures 2 and 8.
- 45 In the position of the shift plate for the initial run of the film the outer end of the portion 123 underlies the aperture 124 and is provided with characters 125 visible through the aperture indicating the proper photographing position of the camera for the initial run of the film strip.
- 50 The portion 123 has, intermediately disposed thereon, a forwardly facing transverse slot 126 which does not lie within the area of the aperture 124 when the shift plate is positioned for the initial run of the camera, but which does lie within the area of the aperture 124 at one end thereof when the shift plate is in its intermediate position, see Figure 2, and at the other end of the aperture when the shift plate is positioned at the other end of its movement for the reverse run of the camera, see Figure 3.
- 55 Consequently, after the initial run of the film 70
- 60
- 65
- 70
- 75

strip is completed and the shift plate is in its intermediate position, the shift plate is manually moved to the end of its movement corresponding with the reverse run of the film strip by engaging the slot 126 through the aperture 124 to move the shift plate to the reverse run position thereof in which the slot 126 lies at the other end of the aperture 124.

When the reverse run of the camera is completed the camera is stopped and the shift plate is shifted to its intermediate position preparatory to reloading the camera.

The cycle of operation of the shift plate 73 and associated parts is illustrated in Figures 14, 15, 16 and 17.

Figure 14 illustrates the position of the parts during the initial run of the film. Figure 15 illustrates the position of the parts at the end of the initial run of the film. Figure 16 illustrates the position of the parts during the reverse run of the film. Figure 17 illustrates the position of the parts at the end of the reverse run of the film which is the same position as that of Figure 15 except with reference to a certain part now to be described.

The portion 123 of the shift plate 73 is provided with a relatively wide transverse channel 127 in its forward face and arranged in this channel is a relatively narrow transverse plate 128 having frictional engagement with the front wall of the casing 1, so that it is only moved with the shift plate by abutment of the transverse edges of the channel 127 with the corresponding edges of the plate 128, thus forming a lost motion connection between the portion 123 of the shift plate and the plate 128. See Figure 8.

Referring to Figure 14 the plate 128 lies substantially out of the area of the aperture 124 in the initial run position of the shift plate. In 40 the shifting of the shift plate from its initial run position to its intermediate position, as shown in Figure 15, the plate 128 remains in its position substantially out of the area of the aperture 124, leaving the slot 126 exposed for shifting the shift plate to the reverse run position thereof, as shown in Figure 16. However, during this latter shift of the shift plate the plate 128 is shifted to cover a substantial area of the aperture 124, leaving, however, the slot 126 exposed.

The portion of the plate 128 visible in the aperture 124 in the latter position thereof is provided with characters 129 disposed reversely to the indicating characters 125 of the portion 123 55 to indicate the proper position of the camera during the reverse run of the film strip. See Figures 3 and 15.

In the movement of the shift plate from its reverse run position to its intermediate position, the plate 128 remains stationary and covers the slot 126, so that the complete exposure of the film is indicated to the operator, thus indicating to the operator that the camera must be reloaded and reset by actuation of the extension 121 to 60 shift the shift plate to its initial run position, the plate 128 being moved substantially out of the area of the aperture 124 during this shift.

The film roll structure of the camera will now be described. See Figures 5 and 12.

Arranged at one vertical end of the film chamber between the frame plate 4 and the cover 2 is a substantially circular film magazine chamber formation 131 disposed on a transverse axis and provided with a peripherally projecting angle portion 132 having one side thereof adjacent

an end of the intermittent film feed guide and disposed normal to the plane thereof and provided with a film slot 133 alined with the feed guide and through which a film 134 passes between the magazine chamber and the adjacent end of the feed guide. See Figures 5 and 11.

The magazine chamber is adapted to receive the film magazine of my invention which consists as follows. See Figures 18, 19 and 20.

A cup shaped body member 135, preferably of sheet metal, is adapted to be engaged in the chamber 131 and is accordingly of substantially circular form and provided with a peripherally projecting angle portion 136 engageable in the angle portion 132 of the chamber 131, the side of said angle portion 136 corresponding with the side of the angle portion 132 having the film slot 133 being provided with a film slot 137 registering with the slot 133 for the passage of the film 134 therethrough.

Disposed within the angle portion 136 and secured with the body member 135, is an angle member 138 forming a rectangular transversely extending enclosure with the angle portion and provided, on the side thereof opposite the leg of the angle portion provided with the film slot 137, with a film slot 139 alined with the slot 137 for the passage of the film 134 therethrough.

Disposed within the aforesaid rectangular enclosure is a pad 141 of yieldable material, such as felt, which is intermediately split for the passage of the film therethrough to provide a light tight passage for the film between the interior and the exterior of the magazine, a light bow spring 142 compressing the pad 141 normal to the plane of the film to insure light tight engagement of the pad with the film.

A cover 143, also preferably of sheet metal, completes the enclosure of the body part and is secured therewith by an interlocking seam comprising an exterior peripheral lip flange 144 on the body member 135 and engaged on one side by the cover and a marginal portion 145 of the cover bent about in overlying relation with the flange 144 and engaging the other side thereof, thus providing a magazine comprising parts permanently sealed together and, as shown, necessitating mutilation of at least one of the parts to open the magazine, to prevent reloading of the magazine for re-use.

A revoluble axle 146 is journaled in central apertures through both the body and cover members 135 and 143, and secured on this axle for rotation thereby is film spool 147 of relatively large diameter, preferably formed of a single strip of sheet metal providing diametrically extending double portions 148 intermediately embracing the axle and secured thereto and providing a slot 149 into which the inner end of a roll of film 151 on the spool is engaged. The axle 146 is bent at a right angle, as designated at 152, exteriorly of the transverse wall of the body member 135 to drive the spool 147 to rewind the film into the magazine as hereinafter described.

The magazine is detachably mounted in the magazine chamber 131 with the peripherally projecting interlocking seam of the body and cover parts overlying the wall of the chamber 131, see Figure 12, the cover 2 retaining the magazine in the magazine chamber when in closed position on the casing 1. When the magazine is mounted in the magazine chamber the film passage alines with the film slot 133 of the magazine for the feeding of the film into and out of the magazine.

Arranged at the vertical end of the film chamber opposite that at which the magazine chamber 131 is disposed, is a substantially circular film receiving chamber formation 153 provided with a substantially tangential film slot 154 aligned with the intermittent film feed guide for the feeding of the film strip 134 therefrom into and out of the receiving chamber. See Figures 5 and 12.

10 Disposed centrally of the chamber 153 and mounted for rotation on the frame plate 4, is a shaft 155, and mounted on this shaft for rotation thereby is a relatively large hub consisting of two spaced discs 156.

15 An arcuate arm 157 is pivotally mounted at one end eccentrically on the hub by means of a rod 158 extending between the discs 156 and secured therewith. The arm 157 is yieldably urged outwardly by means of a torsion spring 159 encircling the rod 158 and having one end engaged with the arm and the other end engaged with a stud 161 mounted on one of the discs 156.

The outer end of the arm 157 is provided with laterally extending portions 162 having their end 25 portions turned outwardly beyond the edges of a coil 163 of the film 134 within the chamber to engage the interior of the chamber wall, thus supporting the intermediate portion of the outer end of the arm 157 which underlies the film 30 coil 163 out of contact with the chamber wall. The said intermediate portion of the outer end of the arm 157 is faced with a suitable friction material 164, such as rubber, for frictional engagement with the interior of the film coil 163 for 35 the winding of the film strip 134 as it is fed into the chamber by the feeding mechanism, the shaft 155 being driven with the feeding mechanism, as hereinafter described, in the direction of rotation of the film coil as the film strip is 40 fed into the chamber and at or above the speed of rotation of the coil.

As the film coil 163 in the receiving chamber increases in thickness, due to the feeding of the film strip thereto, the arm 157 is moved toward 45 the hub until the interior of the film coil engages the hub, transverse slots 165 in the periphery of the discs 156 receiving the laterally extending portions 162 of the arm as the arm moves to its inner position.

50 The film cartridge of my invention comprises the magazine above described loaded with a roll of sensitized film and having one end of the film projecting from the magazine, as shown in Figures 18 and 19.

55 In loading the camera the loaded magazine is placed in the magazine chamber 131 and the projecting end of the film strip is threaded through the intermittent film feed guide and into the receiving chamber 153. The shift plate 73

60 having been set for the initial run of the camera, the cover 2 is closed and the initial run of the film strip is made in which the film is fed from the magazine into the receiving chamber 153, the axle 146 of the film magazine being free to rotate 65 with the film roll in the magazine and the shaft 155 being driven to wind the film strip in the receiving chamber during this run of the film strip.

The mechanism is automatically stopped at the 70 end of its initial run and before the film strip completely leaves the spool 147.

The shift plate 73 is then set for the reverse run of the camera, and during the reverse run the film is fed from the receiving chamber 153 back into the magazine, the shaft 155 being free

to rotate with the film coil 162 and the axle 146 being driven to wind the film strip back into the magazine during this run of the film strip, the magazine with the exposed film therein being removed for development of the film therein and another loaded magazine being placed in the camera for exposing its film.

The axle 146 of the film magazine and the shaft 155 of the receiving chamber are alternately driven with the feeding mechanism, the shaft 155 during the initial run direction of operation of the feeding mechanism and the axle 146 during the reverse run direction of operation of the feeding mechanism, in the following manner. See Figures 8, 12 and 13.

A rotatable shaft 166 is mounted on the frame plate 4 in coaxial relation with the axle 146 and has its outer end enlarged and transversely slotted, as designated at 167, see Figures 5 and 12, to engage the angle portion 152 of the axle for driving the axle from the shaft 166.

A substantially vertical revoluble shaft 168 is disposed between the frame plates 4 and 5 and has a spiral gear 169 on the intermediate portion thereof which meshes with the cam shaft gear 43 for the driving of the shaft 168 therefrom. Spur pinions 171 are secured on the ends of the shaft 168 and the shafts 155 and 166 are driven from the pinions 171 in the following manner, and, inasmuch as the drives of the shafts 155 and 166 are similar, the drive between the shaft 155 and the adjacent pinion 171 will be described, it being understood that the description is applicable to the drive of the shaft 166.

Revolvably mounted on the shaft 155 is a bored cup shaped member 172, and disposed within the enclosure thereof and keyed on the shaft 155 is a disc 173 provided with peripheral radial cam formations 174 spaced angularly thereabout. See Figures 12 and 13. Balls 175 are disposed between the cam formations 174 and the interior surface of the cup-shaped member 172, to form an overrunning or one way driving clutch, the cam formations acting to wedge the balls against the member 172 to form a driving connection between the member 172 and the disc 173 when the member 172 is rotated in one direction and to release the same when the member 172 is rotated in the opposite direction. A circular plate 176 is secured on the inner end of the shaft 155 by a screw 177 and retains the balls 175 in the cam formations.

The member 172 is provided with an exterior hub 178 upon which a crown gear member 179 is rotatably mounted. The crown gear meshes 55 with the adjacent pinion 171 for the driving thereof, and the web of the crown gear is disposed between and in frictional engagement with the transverse wall of the cup shaped member 172 and a friction disc 181 slidably keyed on the hub of the member 172. A spring member 182 is secured on the hub of the member 172 and maintains frictional contact between the webs of the gear member 179, the member 172 and the disc 181, thus providing a friction slip driving connection between the gear member 179 and the member 172.

Thus, is provided friction slip one way driving connections between the shaft 168 and the shafts 155 and 166, the arrangement being such that 70 the shaft 155 is driven in the direction to wind the film strip in the receiving chamber and the shaft 166 is free to rotate with the film roll in the magazine during the initial run of the camera and the shaft 166 is driven to wind the film in the 75

magazine and the shaft 155 is free to rotate with the film roll in the receiving chamber during the reverse run of the camera, the friction slip driving devices permitting slippage when the film roll drives overrun the speed of rotation of the film rolls as the film strip is wound thereon.

While I have herein shown and described my invention, I do not wish to be limited to the precise details shown and described as changes 10 may readily be made without departing from the spirit of the invention, but having thus described my invention, I claim as new and desire to secure by Letters Patent the following.

1. In a motion picture camera the combination 15 with means for progressively exposing one longitudinal section of a film strip in one direction and subsequently progressively exposing another longitudinal section of the film strip in the other direction including film feeding mechanism 20 and shiftable means operative to reverse the direction of film feed by said feeding means relative to the camera casing, manually releasable means operative to stop operation of said feeding mechanism, and means responsive to a predetermined run of said feeding mechanism and adapted 25 to shift said shiftable means and to render said stopping means operative at the end of said predetermined run of said feeding mechanism.

2. In a motion picture camera the combination 30 with means for progressively exposing one longitudinal section of a film strip in one direction and subsequently progressively exposing another longitudinal section of the film strip in the other direction including film feeding mechanism and 35 shiftable means operative to reverse the direction of film feed by said feeding means relative to the camera casing, manually releasable means operative upon shifting of said shiftable means to stop operation of said feeding mechanism, and means 40 responsive to a predetermined run of said feeding mechanism and adapted to shift said shiftable means and render said stopping means operative at the end of said predetermined run of said feeding mechanism.

3. In a motion picture camera the combination 45 with means for progressively exposing one longitudinal section of a film strip in one direction and subsequently progressively exposing another longitudinal section of the film strip in the other direction including film feeding mechanism and shiftable means operative to reverse the direction of film feed by said feeding means relative to the camera casing, means operative, upon shifting of said shiftable means to an intermediate position of its movement, to stop operation of said feeding mechanism and releasable upon shifting of said shiftable means from said intermediate position, and means responsive to a predetermined run of said feeding mechanism and adapted 55 to shift said shiftable means to said intermediate position at the end of said predetermined run, said shiftable means being manually shiftable from said intermediate position.

4. In a power driven camera the combination 60 with means for progressively exposing one longitudinal section of a film strip in one direction and subsequently progressively exposing another longitudinal section of the film strip in the other direction including reversible film strip feeding 65 means and reversing means for driving said feeding means and shiftable to operate said feeding means in opposite directions, a stop device controlling operation of said feeding means and provided with spaced opposing stop formations oper- 70 ative to stop operation of said feeding means in

opposite positions of said stop device and permitting operation of said feeding means in an intermediate position of said stop device, yieldable means connected with said shiftable means for operating said stop device to its opposite 5 stopping positions with movement of said shiftable means to its opposite positions, control devices accessible from opposite sides of the camera, one way operative connections between said control devices and said stopping device and operative oppositely on said stopping device and means limiting movement of said control devices in their operative directions whereby one control device is operative to move said stop device from one end of its movement to said intermediate position and the other control device is operative to move said stop device from the other end of its movement to said intermediate position.

5. In a motion picture camera the combination 20 with means for progressively exposing one longitudinal section of a film strip in one direction and subsequently progressively exposing another longitudinal section of the film strip in the other direction with the camera in a relatively upside down position including means shiftable to feed the strip in opposite directions relative to the camera casing, of means operatively connected with said shiftable means and adapted to indicate the proper position of the camera for the exposure of the instant longitudinal section of the film strip.

6. In a motion picture camera the combination 35 with means for progressively exposing one longitudinal section of a film strip in one direction and subsequently progressively exposing another longitudinal section of the film strip in the other direction with the camera in a relatively upside down position including means shiftable to feed the strip in opposite directions relative to the camera casing, of visually observable means operatively connected with said shiftable means and adapted to indicate the proper position of the camera for the exposure of the instant longitudinal section of the film strip.

7. In a motion picture camera the combination 40 with means including reversible film strip feed mechanism for progressively exposing one longitudinal section of a film strip in one direction and subsequently progressively exposing another 50 longitudinal section of the film strip in the other direction and including means shiftable to feed the strip in opposite directions relative to the camera casing, of two view finders facing in the same direction and disposed on the camera on opposite sides of the exposure region thereof, and means operatively connected with said shiftable means and adapted to alternately render said view finders inoperative.

8. In a power driven motion picture camera 60 the combination with means including reversible film strip feed mechanism for progressively exposing one longitudinal section of a film strip in one direction and subsequently progressively exposing another longitudinal section of a film strip in the opposite direction including reversing driving means shiftable to operate said feed mechanism in opposite directions, of two view finders facing in the same direction and disposed on the camera on opposite sides of the exposure region thereof, and means operatively connected with said shiftable means for alternately rendering said view finders inoperative.

9. In a power driven motion picture camera 75

- the combination with means including reversible film strip feed mechanism for progressively exposing one longitudinal section of a film strip in one direction and subsequently progressively exposing another longitudinal section of the film strip in the other direction and including means shiftable to feed the strip in opposite directions relative to the camera casing, of means accessible from opposite sides of the camera for controlling operation thereof, two view finders facing in the same direction and disposed on the camera on opposite sides of the exposure region thereof, means operatively connected with said shiftable means and operative to render said controlling means inoperative to control the feeding mechanism alternately from opposite sides of the camera, and means also operatively connected with said shiftable means and operative to alternately render said view finders inoperative.
- 5 10. In a power driven motion picture camera
- 10 15. means inoperative to control the feeding mechanism alternately from opposite sides of the camera, and means also operatively connected with said shiftable means and operative to alternately render said view finders inoperative.
- 15 20. 10. In a power driven motion picture camera

the combination with means including reversible film strip feed mechanism for progressively exposing one longitudinal section of a film strip in one direction and subsequently progressively exposing another longitudinal section of the film strip in the other direction including reversing driving means shiftable to operate said feed mechanism in opposite directions, means accessible from opposite sides of the camera for controlling operation of the camera, two view finders 10 facing in the same direction and disposed on the camera on opposite sides of the exposure region thereof, means operatively connected with said shiftable means and operative to render said controlling means inoperative to control said feeding 15 mechanism alternately from opposite sides of the camera, and means also operatively connected with said shiftable means and operative to alternately render said view finders inoperative.

ALBERT S. HOWELL. 20
